VEHICLE DOOR LOCK HANDLE

Frederick W. Crew, Detroit, Mich.

Application June 3, 1943, Serial No. 489,561

2 Claims. (Cl. 70—150)

My invention pertains to a lock handle for the outside manual and key control of door locks which may be latched from the inside, and to a method of assembly.

It is an object of my invention to provide an improved handle for the combined direct manual or key control of a door lock from the outside, even when it has been latched from the inside, and to an improved method of assembly therefor.

It is also an object of my invention to provide such a door lock handle assembly which will be a simple rugged construction, convenient to assemble and durable in operation.

It is a further object of my invention to provide an improved door lock handle for the combined direct manual and key control from the outside of a door lock having a larger radius for the key controlled or releasing mechanism.

The invention itself, however, both as to its construction and its use, together with additional objects and advantages thereof, will best be understood from the following description of specific embodiments, when read in conjunction with the accompanying drawing, in which:

Fig. 1 is a side elevational view showing an assembled handle for the outside manual or key control of a door lock in accordance with my invention;

Fig. 2 is a longitudinal sectional view taken axially through the handle assembly;

Fig. 3 is an enlarged cross-sectional view taken on line 3—3 of Fig. 1;

Fig. 4 is a cross-sectional view taken on line 4—4 of Fig. 1; and

Fig. 5 is a diagrammatic view illustrating operative relation of the relatively movable parts of the handle.

Referring more specifically to Fig. 1, I have illustratively disclosed my improved door lock handle for combined outside manual and key control, comprising a handle 11 having an elongated hub and extension 13 projecting from one side and suitably conformed at the end 15 as by being non-circular or square in cross-section, for operative engagement into a similarly shaped aperture in any lock member, such as a roll-back, to be actuated from the handle, as will be readily understood. As shown in Fig. 1, the hub extension 13 of the handle also carries a cam sleeve 17 rotatively thereon and having a laterally projected cam or camming projection 19 and which may be rotated through a limited angle, in a manner to be described, for performing some other operation in a lock, such as releas-

ing a dog or latch, in response to the insertion of a proper key by an authorized person.

As shown in Figs. 2, 3 and 4, the hub extension 13 may preferably be a tubular member shaped at the extended end to the desired non-circular cross-section 15 and having the handle 11 die cast with a hub 16 on the other end, or these may be formed integral if desired. The split cam sleeve 17 is of a substantially cylindrical conformation adapted to fit loosely upon the extension, and the cam 19 is a lug projecting from one side thereof. A slot 21, elongated circumferentially in the side wall of the cam sleeve, is disposed substantially in alignment with a slot 23 in the side wall of the tubular extension. Slot 21 extends a substantially lesser distance circumferentially in the cam sleeve than does the slot 23 in the extension. A lock barrel 25 is rotatively disposed in the aperture in the handle 11 in a bushing 27 which is provided with two tumbler recesses 29, adapted to receive the tumblers 31. The bushing 27 is connected, by interconnecting parts 33, with the tubular extension member.

Operatively connected to the lock barrel, as by diecasting together, is a spindle 35 which extends in the aperture in the tubular extension and has a hole 37 disposed at a suitable axial position so that when fully inserted it is in alignment with the slot 23 in the tubular extension. When the hole 37 and the two slots 21 and 23 are brought into axial alignment, a knurled pin 39 is inserted through these slots and is pushed snugly into the hole in the spindle to prevent relative longitudinal displacement of the spindle, the tubular extension, and the cam sleeve. A certain amount of relative angular rotation is provided, as determined by the circumferential lengths of these adjacent slots, so that sufficiently turning the lock spindle 35 by a key 41 may turn the cam sleeve 17 on the tubular extension, while the latter remains stationary. The cam sleeve 17 has at all times a certain amount of free rotary or angular movement on the tubular member 13.

The lock handle assembly is rotatively installed in a vehicle door, in a usual manner, with the handle 11 being exposed on the outside, and the operative end 15 and cam 19 being operatively engaged with parts of the lock to be controlled by the handle 11 and the lock 25 respectively. The relation of the installed handle to parts of the lock to be controlled, shown dotted, is represented diagrammatically in Fig. 5. The element shown dotted, and designated 43, repre-

sents any part of a lock, such as a "rollback" to be rotated from the inner end 15 by turning the outside handle. The dotted element 45 represents a lock part, such as a latching dog, engaged with the cam 19 to be controlled from the outside by means of a key 41. As will be understood, the elements 43 and 45 may be any parts to be moved or actuated.

It is apparent that within the scope of my invention modifications and different arrangements may be made other than herein disclosed, and the present disclosure is illustrative merely, the invention comprehending variations thereof.

I claim:

1. The combination in a door lock handle for the outside manual and key control of a door lock of, a handle having a hub extension projecting from one side, the extended end of said hub extension being adapted for operative engagement for controlling the movement of a lock member to be actuated, an aperture through the handle and into the extension, a lock barrel in the handle aperture with its key aperture disposed on the side opposite from said hub extension; a spindle connected to said lock barrel and rotatively disposed in the aperture in said hub extension; a transverse hole in the extended end of said spindle; a circumferentially extending slot in the hub extension in alignment with said transverse hole; a cam sleeve rotatively disposed

upon the hub extension, a camming projection on said sleeve, a circumferentially extending slot in said cam sleeve, a pin in the transverse hole in the spindle and projecting through the slot in the hub extension for holding the spindle from longitudinal movement and projecting still further into the slot in the cam sleeve for holding the sleeve from longitudinal movement and for rotating the sleeve for accomplishing a control operation.

2. A combination manual and key control for door locks comprising, three relatively movable concentrically disposed members, the intermediate one of said members having one end conformed for operative coupling with a device to be controlled and its other end being adapted for convenient manipulation, the outermost of said concentrically disposed members being conformed for operative engagement with a device to be controlled, slack motion-coupling means for transmitting operative movement from one end of the central member to the outermost concentric member while permitting the latter to have a limited amount of free angular movement, a lock barrel disposed in alignment with the other end of the central member, and said other end of said centrally disposed member being connected with said lock barrel for operation by a person having a suitable key.

FREDERICK W. CREW.
